UNITED STATES PATENT OFFICE.

FREDERICK GOERTZ, OF NEWARK, NEW JERSEY, ASSIGNOR TO AUG. GOERTZ & CO., A CORPORATION OF NEW JERSEY.

BAG-FRAME.

1,075,560.

Specification of Letters Patent.

Patented Oct. 14, 1913.

Application filed February 2, 1911. Serial No. 606,137.

To all whom it may concern:

Be it known that I, FREDERICK GOERTZ, a citizen of the United States, residing at Newark, in the county of Essex and State 5 of New Jersey, have invented certain new and useful Improvements in Bag-Frames; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates, generally, to improvements in bag-frames; and, the present invention has reference, more particularly, to a novel form of frame for bags, satchels, and the like, in which each one of the hinged 20 or pivotally connected frame-sections is made in three parts which are suitably secured together at the corners of the bag-frame section, instead of making each bag-frame section in one integral piece, as heretofore.

25 The present invention has for its principal object to provide a novel and simply constructed bag-frame section comprising three separately made parts or members, 30 two of which are suitably secured to the end-portions of the third member by means of suitable fastening or securing means, so as to provide a frame-section of the general shape and conformation formed with a central member and the depending end or leg-members.

35 The invention has for its further object to provide a bag-frame section which is especially adapted to be made from a more 40 or less expensive metal, and in the manufacture of the three parts of which the waste of metal is trifling, and in fact there is hardly any waste, so that to the manufacturer there is a very great saving in the 45 cost of metal, and there is also a saving in time and labor, owing to the readiness with which the three members of the frame-section can be assembled.

50 The invention has for its further object to provide a three-part frame-section of the general character hereinafter more fully set forth, in the manufacture of which the leg-members of different frame-sections may all be of the same size and length, but that

the central members of the frame-sections 55 may be of different lengths; the manufacturer thereby being enabled to use but one set of dies for all the frame-sections, instead of a large number of dies, as heretofore, where the parts of the frame-sections are all 60 made in one integral piece.

The invention has for its further object to provide a bag-frame section made as hereinabove stated, in which owing to the manner in which the leg-members are attached to the end-portions of the central member, the said central member will lie in a plane somewhat lower than the plane of the leg-members, thus providing off-sets or shoulders at or near the corners of the 70 frame-sections, and whereby the said central member may be leather-covered, the face of said covering being flush with the metal-exposed and highly polished or gold-plated faces of the two leg-members of the bag- 75 frame section.

Other objects of this invention not at this time more particularly enumerated will be clearly understood from the following detailed description of the present invention. 80

With the various objects of this invention in view, the said invention consists, primarily, in the novel bag-frame-section hereinafter set forth; and, the invention consists, furthermore, in the novel arrangements and combinations of the various parts, 85 as well as in the details of the construction of the same, all of which will be more fully described in the following specification, and then finally embodied in the clauses of the 90 claims which are appended to and which form an essential part of this specification.

The invention is clearly illustrated in the accompanying drawings, in which:—

Figure 1 is a face view of a frame-section 95 made according to and embodying the principles of the present invention, a portion of the central member of the frame-section being represented as being leather-covered; and Fig. 2 is a view of the inner face of 100 the completed bag-frame-section. Fig. 3 is a detail horizontal sectional representation of a portion of the central member of the frame-section, with its leather covering, and one of the leg-members, said section being 105 represented as taken on line 3—3 in said Fig. 2, looking in the direction of the arrow, and said figure showing the parts of

said members which form the corners of the bag-frame-section permanently secured together by means of solder; and Fig. 4 is a similar sectional representation of the same 5 parts, but showing the said parts secured together by means of rivets.

Similar characters of reference are employed in all of the above described views, to indicate corresponding parts.

10 Referring now to the several figures of the drawings, the reference-character 1 indicates a complete bag-frame section showing one embodiment of the various features of the present invention, the said frame-section 15 comprising a main central member 2, and a pair of leg-members 3, all of which are made from suitable sheet-metal. As will be understood, the said main or central member 2 may be of any desired and suitable length, 20 but is quite narrow in width, the end-portions 4 of the said member 2 being of any suitable marginal configuration. Along its upper marginal and longitudinally extending edge-portion the said main or central 25 member 2 is provided with an inwardly extending flange, as 5, extending at a right angle from said marginal edge-portion, and of suitable width, said flange 5 forming the upper surface or face of the said main or 30 central member 2. As shown, the said flange or right-angled projection 5 is preferably of such length, that its ends 6 both terminate some distance before the marginal end-portions 4 are reached, substantially as shown 35 in Fig. 2 of the drawings. The two leg-members 3, which are also narrow in width, are also formed along one of their long marginal edge-portions with the right-angled flanges or projections 7, the upper 40 end-portions 8 of which are made so as to correspond with the marginal configuration of the marginal end-portions 4 of the main or central member 2, and each end-portion 8 terminating in a horizontally extending 45 right-angled flange or projection 9 extending along the upper marginal edge-portion 4 of said main or central member 2, and terminating upon the end-portion of the right-angled flange or projection 5, as clearly 50 shown in the several figures of the drawings. At their lower end-portion the said right-angled flanges or projections 7 of the leg-members 3 terminate in the usual perforated 55 pintle-receiving ears 10, by means of which a pair of the completed frame-sections may be pivotally connected in a hinge-like manner, so as to produce the complete bag-frame.

As shown, the upper end-portions and the 60 flange-portions 8 and 9 of the respective leg-members practically provide suitable pockets or receiving portions in which the end-portions of the said main or central member 2 are arranged, said portions of the 65 separately made parts being rigidly secured

by means of solder, as 11, as clearly shown in Fig. 3 of the drawings. One manner of securing and flowing the solder between the registering face-portions of the respective members 2 and 3 is by providing the main 70 or central member 2 with suitable openings, as 12, in which the solder is placed; and, by the application of heat thereto, the solder is melted and caused to flow between the assembled parts, which upon the cooling and 75 hardening of the solder rigidly and positively secures the said leg-members to the said main or central member, and thereby produces the complete frame-section shown in said Figs. 1 and 2 of the drawings. At 80 the same time, owing to the overlapping arrangement of the end-portions of the leg-members and the central member at the corners of the frame-section, a shoulder or offset 85 13 is formed upon the face of the bag-frame section near each corner, so that the outer face of the main or central member 2 is in a plane a trifle lower than the plane of the outer faces of the two leg-members; as will be clearly evident, and the said main or 90 central member 2 can therefore be neatly inclosed in a covering 14 of leather, or any suitable material, flush with the outer faces of the said leg-members 3, which may be highly polished, or silver or gold-plated, so 95 as to provide a bag-frame section of great beauty and of enhanced value.

It will also be clearly evident that with bag-frames of different sizes, aside from the great saving in material over the old forms 100 of bag-frame sections, the central member and the leg-members of which are made in one piece, the central or main member 2 may be in different lengths, while the lengths of all the leg-members of the different sizes 105 of bag-frames may be the same, thus greatly reducing the cost of construction, because only one set of dies is necessary to produce the leg-members for the different sizes of bag-frames.

110 In lieu of securing the assembled corner-portions of the main or central member 2 and the leg-members in their rigidly fastened relation by means of solder as hereinabove described, these parts may be rigidly 115 connected by means of suitably formed and suitably disposed pins or rivets 15, as clearly indicated in Fig. 4 of the drawings.

120 Of course I am aware that some changes may be made in the arrangements and combinations of the various parts, as well as in the details of the construction of the same, without departing from the scope of the present invention as set forth in the foregoing specification, and as defined in the claims 125 which are appended thereto. Hence, I do not limit my invention to the exact arrangements of the parts as described in the said specification, nor do I confine myself to the exact details of the construction of the said 130

parts as illustrated in the accompanying drawings.

I claim:—

1. A bag-frame section comprising a separate main or central member, a flange extending at a right angle from one of the long marginal edge-portions of said member, said flange terminating at points removed from the marginal end-portions of said member, and separate leg-members, a flange extending at a right angle from one of the long marginal edge-portions of each leg-member, each leg-member having an end-portion overlapping an end-portion of said main or central member, and the flange of each leg-member extending around the marginal end-portion of the main or central member and in contact therewith, the flange of each leg-member having a horizontally disposed flange-portion overlapping and registering with the end-portion of the flange of said main or central member and in contact therewith, and means for rigidly securing said overlapping portions of the said main or central member and said leg-members together to provide a complete frame-section.

2. A bag-frame section comprising a separate main or central member, and separate leg-members, each leg-member having an end-portion overlapping an end-portion of said main or central member, and means for rigidly securing said overlapping portions together to provide a complete frame-section, said overlapping portions of the main or central member and said leg-members providing the frame-sections with shoulders forming a depressed surface extending over the entire outer face-portion of the said cen-

tral member, and a covering of flexible material in said depressed face-portion.

3. A bag-frame section comprising a separate main or central member, a flange extending at a right angle from one of the long marginal edge-portions of said member, and separate leg-members, a flange extending at a right angle from one of the long marginal edge-portions of each leg-member, each leg-member having an end-portion overlapping an end-portion of said main or central member, and means for rigidly securing said overlapping portions together to provide a complete frame-section, said overlapping portions of the main or central member and said leg-portions providing the frame-section with shoulders forming a depressed surface extending over the entire outer face-portion of the said central member, and a covering of a flexible material in said depressed face-portion.

4. A bag-frame section comprising a main or central member, and leg-members, said leg-members having their outer metal surfaces exposed, and said main or central member and the leg-members at the corners of the frame-section being provided with shoulders forming a depressed surface upon the outer face-portion of the said central member, and a covering of flexible material in said depressed face-portion.

In testimony, that I claim the invention set forth above I have hereunto set my hand this 30th day of January, 1911.

FREDERICK GOERTZ.
